UNITED STATES PATENT OFFICE.

ROBERT B. ROGERS, OF SOMERVILLE, MASSACHUSETTS.

DESIGN FOR A CUFF-BUTTON PROTECTOR.

46,237.

Specification for Design.

Patented Aug. 4, 1914.

Application filed May 21, 1914. Serial No. 840,131. Term of patent 3½ years.

To all whom it may concern:

Be it known that I, ROBERT B. ROGERS, a citizen of the United States, residing at Somerville, county of Middlesex, State of Massachusetts, have invented a new, original, and ornamental Design for a Cuff-Button Protector, of which the following is a specification, reference being had to the accompanying drawing, forming part thereof.

The figure is a plan view of a cuff button protector illustrating my new design.

I claim:

The ornamental design for a cuff button protector, as shown.

ROBERT B. ROGERS.
